US0D1061009S

(12) United States Design Patent (10) Patent No.: US D1,061,009 S
(45) Date of Patent: * Feb. 11, 2025

(54) BAG

(71) Applicant: YETI Coolers, LLC, Austin, TX (US)

(72) Inventors: Roy Joseph Seiders, Austin, TX (US);
Dustin Bullock, Austin, TX (US)

(73) Assignee: YETI Coolers, LLC, Austin, TX (US)

() Term: 15 Years

(21) Appl. No.: 29/783,118

(22) Filed: May 11, 2021

Related U.S. Application Data

(63) Continuation of application No. 29/705,676, filed on Sep. 13, 2019, now Pat. No. Des. 918,570, which is

CLAIM

The ornamental design for a bag as shown and described.

DESCRIPTION

FIG. 1 is a top, front, left perspective view of a bag showing our new design;

FIG. 2 is a front view thereof;

FIG. 3 is a rear view thereof;

FIG. 4 is a left side view thereof;

FIG. 5 is a right side view thereof;

FIG. 6 is a top, front, left perspective view of the bag showing our new design shown in an alternative configuration;

FIG. 7 is a rear perspective view of the bag shown in another alternative claimed configuration;

FIG. 8 is a rear perspective view of the bag showing our new design shown in another alternative claimed configuration; and,

FIG. 9 is a top, front perspective view of the bag shown in another alternative claimed configuration.

The portions of the bag shown in broken lines form no part of the claimed design.

1 Claim, 9 Drawing Sheets

Related U.S. Application Data

a continuation of application No. 29/660,156, filed on Aug. 17, 2018, now Pat. No. Des. 859,813.
